SWEEPING MACHINE

Peter N. Eichhamer, St. Louis, Mo.

Application October 18, 1933, Serial No. 694,925

1 Claim. (Cl. 15—82)

This invention relates to a certain new and useful improvement in sweeping-machines and the like.

My invention has for its chief object the provision of a machine of the class mentioned having a rotary brush that may, to compensate for wear, be readily bodily adjusted relatively to the carriage of the machine for effective ground engagement.

10. My invention has for a further object the provision of a machine of the class stated that may be inexpensively and economically manufactured, that may be readily and conveniently manipulated and the brush rotarily driven in any selected or adjusted position thereof, and which is efficient in the performance of its intended functions.

20. And with the above and other objects in view, my invention resides in the novel features of form, construction, arrangement, and combination of parts presently described and pointed out in the claim.

In the accompanying drawings,—

25. Figure 1 is a side elevational view of a sweeping-machine embodying my invention;

Figure 2 is an enlarged plan view, partly broken away and in section, of the machine;

30. Figure 3 is a vertical sectional view of the machine taken approximately on the line 3—3, Figure 2, looking in the direction of the arrows, showing the machine handle forwardly swung, and illustrating a worn brush in adjusted position for ground engagement;

35. Figures 4 and 5 are detail sectional views of the machine taken approximately along the lines 4—4 and 5—5, Figure 2, respectively; and

40. Figure 6 illustrates the inner side of one of the carriage-frames, showing the adjustability of the brush bodily for compensating for wear of its bristles.

45. Referring now more in detail and by reference characters to the drawings, which illustrate a preferred embodiment of my invention, the machine includes a carriage A which comprises a pair of frames B, B', each frame B, B', in turn, comprising a pair of approximately oblong-rectangular metallic side-plates b, b', each undercut and formed adjacent its rear end and on a side face with spaced upstanding lugs 1. Fitting between

50. the lugs 1 and bolted or otherwise fixed to the respective plates b, b', as shown, are ears 2 upwardly presented from a tie-plate 3 seated in the undercut portions of the plates b, b', for rigidly securing the same together in spaced parallel relation. The inner plates b' of the respective frames

B, B', are also provided with inwardly presented sockets 4, in which are seated and secured the opposite ends of a cross-bar 5 for rigidly, in turn, retaining the frames B, B', together in spaced parallel relation, and bolted or otherwise suitably fixed to the respective plates 3, are suitable rotary brackets 6, in which are arranged for rotation suitable castors 7.

The plates b, b' of frame B are formed with suitable registering bearing-openings, in which is seated, and by set-collars or the like 8 secured, an axle-shaft 9, the plate b' being formed on its inner face and about the shaft 9 with an annular boss or enlargement 10 counterbored, as at 11, to accommodate a projecting end-portion of the hub 12 of a housing-member which comprises a disc-shaped body-portion 13 provided marginally with a laterally inwardly presented tread-flange or ground-engaging rim 14, and to facilitate free rotary movement of such member, suitable ball 20 or other non-friction bearings 15 are interposed between the hub 12 and shaft 9.

25. Formed on the inner face of the disc 13, is a boss or enlargement 16, and flatwise seated upon and, as at 17, bolted, pinned, or otherwise fixed to the boss 16 and surrounding the hub 12, is a gear-wheel 18.

30. Having a hub 19 seated on and surrounding the boss 16 and fitting at its outer margin within the confines of the tread-flange 14, as shown, is a disc 20, which with the flanged member 13 forms a housing for the gear 18 and its associated parts presently described.

35. Fixed on and surrounding the hub 19, is a toothed ring 21, and pivotally attached to suitable pairs of ears 22, 23, provided on the inner frame-plate b', are arms 24, 25, respectively each cut away, as at 27, upon a side face and at its free end and thereby reduced in thickness to fit between the ring 21 and the disc 20 for rigidly 40 securing the disc 20 in housing forming relation with the tread-member 13. The arms 24, 25, are preferably yieldingly, as by a coiled spring or other suitable resilient member 26, held in disc-securing co-operation, and, for purposes presently appearing, the upper arm 24 is formed in the cut-away portion of its free end with an arcuate series of teeth 27 for interlocking engagement with the toothed ring 21.

45. Fixed upon the inner face of the disc 20 adjacent its periphery, is a bearing-bracket 28, and projecting through and at an end having a bearing for rotation in registering openings provided for the purpose in the disc 20 and bracket 28, is a stub-shaft 29 provided on its outwardly pro-

50. 55

jecting end with a non-circular stud 29' on which is fitted a two-part socket comprising a main or body-portion 30 providing a seat or support for one end of a shaft 31 forming part, and supporting the bristles 32, of a cylindrical brush C. Fitting over the seated end of shaft 31 and completing the socket, as substantially shown by dotted lines in Figure 2, is an arcuate cap or complementary portion 33, a bolt 34 fitted through

10 the socket parts 30 and 33 and the seated shaft-end, as best seen in Figure 5, rigidly securing the same detachably together.

15 Fixed on the stub-shaft 29 within the housing formed by the disc 20 and tread-member 13 and meshing with the gear 18, is a brush-driving pinion 35.

20 The opposite carriage-frame B' is similarly equipped with an axle-shaft 9, on which in like manner is mounted a rotary flanged tread-member 13' and a relatively stationary disc 20', and fixed on the disc 20', is a second toothed ring 21, with which and with the disc 20' are engageable a second pair of opposed pivoted arms 24, 25, in the same manner as previously described.

25 Formed on the outer face of the disc 20', is a socket 36 provided centrally with a stud 37, and fitted for rotation in the socket 36 and on the stud 37 and disposed in opposed registering relation with the socket supported on the stub-shaft 30. 29, is a similar two-part socket-member comprising the complementary portions 30', 33', for in like manner securely supporting the other or opposite end of the brush-shaft 31.

30 Upon the respective inner faces of the discs 20, 20', are opposed sockets 38, in which are seated and suitably secured the opposite ends of a cross-bar 39 for rigidly maintaining the discs 20, 20', in non-rotatable relation the one to the other and for unitary rotatable adjustment thereof, for purposes presently appearing, relatively to the tread-members 13, 13'.

35 Adjacent their rear end, the opposite plates b' of the frames B, B', are provided with inwardly presented annular studs 40, on which are pivoted the legs 41 of a yoke 42, fixed to which, as at 43, is a manipulating handle-bar 44, an apertured bracket or stirrup 45 formed preferably on the inner plate b' of frame B' about the stud 40 limiting the swingable movement of the handle-bar 50 44 relatively to the carriage-frames B, B'.

45 In use and operation, the casters 7 and the rotary flanged tread or ground engaging members 13, 13', enable convenient propulsion or pushing of the machine rollably over the area to be swept, cleaned, or otherwise worked. On such movement of the tread-member 13 and its attached gear 18, the brush C will be rotarily actuated through and by the meshing drive pinion 35.

50 For effective sweeping or other such work, it will, of course, be understood that the tips of the bristles of the brush C should be located for ground engagement, and such engagement is very conveniently obtained through the interengaging relation between the toothed rings 21 and the

toothed arms 24 and the eccentric mounting of the brush C relatively to the axis of rotation of the tread-members 13, 13', or, in other words, through the angular disposition of the brush C relatively to the shafts 9.

5 Obviously, on the arms 24 being lifted out of engagement with the rings 21, the discs 20, 20', may in unison be rotarily shifted relatively to the shafts 9 and the brush C, in turn, axially shifted for initially properly locating the bristle-tips for efficient sweeping action, the brush C being adjustably secured in such position on re-engagement of the arms 24 with the rings 21. In like manner, and as shown in Figure 6, the brush C may be bodily shifted or adjusted from time to time in an annular path relatively to the tread-members 13, 13', and the carriage during the life of the brush and as its bristles wear from use for disposing the worn bristles for proper ground engagement.

10 20 25 It may be added that, while brush C may be of any suitable type and structure, preferably in the present brush C, the bristles 32 are looped about a retaining-wire 46, which, in turn, is spirally disposed about the shaft 31 in a correspondingly formed groove 47 provided for the purpose in the surface of the shaft.

20 30 35 It will also be understood that the driving gears 18, 35, are preferably omitted from the opposite housing for facilitating turning movements of the machine, that, while not here specifically shown, an abrading drum or analogous cleaning, scouring, or other such member could be readily interchanged for the brush C, and that other changes and modifications in the form, 35 construction, arrangement, and combination of the several parts of the machine may be made and substituted for those herein shown and described without departing from the nature and principle of my invention.

40 Having thus described my invention, what I claim and desire to secure by Letters Patent is,—

45 In a machine of the class described, a carriage comprising a pair of frames fixed together in spaced parallel relation, shafts supported in alignment one with the other by the frames, housings each including a main disc provided marginally with a lateral ground-engaging flange and having a hub journaled for rotation on a respective shaft, and a second disc peripherally 50 loosely embraced by said flange and disposed for rotary adjustment about said respective shaft, a cylindrical brush lengthwise disposed intermediate the frames in radially offset relation to said shafts and carried by the second discs for axial 55 rotation, means for axially rotating the brush on rotary movement of the first discs, and means for rigidly retaining the second discs in rotarily adjusted position relatively to the shafts, said means comprising a toothed ring fixed on one of the second discs, and a toothed arm pivoted on the respective frames for engagement with the ring.
